RUDOLF E. HELLMUND, OF PITTSBURGH, AND HURD T. MORRIS, OF WILKINSBURG, PENNSYLVANIA, ASSIGNEES TO WESTINGHOUSE ELECTRIC AND MANUFACTURING COMPANY, A CORPORATION OF PENNSYLVANIA.

SYSTEM OF CONTROL.

1,311,859.

Specification of Letters Patent. Patented July 29, 1919.

Application filed March 13, 1916. Serial No. 83,744.

To all whom it may concern:

Be it known that we, RUDOLF E. HELLMUND, a subject of the Emperor of Germany, and a resident of Pittsburgh, in the county of Allegheny and State of Pennsylvania, and HURD T. MORRIS, a citizen of the United States, and a resident of Wilkinsburg, in the county of Allegheny and State of Pennsylvania, have invented a new and useful Improvement in Systems of Control, of which the following is a specification.

Our invention relates to systems of control, and it has special relation to the control of alternating-current motors of the commutator type.

The object of our invention is to provide a system of the above-indicated character which shall embody certain novel features for effecting more reliable and satisfactory operation of the system.

Heretofore, in systems of the type employing alternating-current, commutator motors that are initially connected as repulsion motors and subsequently are changed over to a doubly-fed connection, it has been common practice either to manually control the system throughout, whereby there is no assurance that the change to a doubly-fed connection is effected under proper or permissible commutating conditions, or to completely automatically control the system, whereby relatively expensive and complicated systems have obtained.

In a prior application of H. T. Morris, Serial No. 32,183, filed June 4, 1915, and patented Aug. 14, 1917, No. 1,236,742, said H. T. Morris being one of the applicants in the present application, is disclosed a system of control wherein alternating-current motors of the compensated, commutator type are started and manually accelerated as repulsion motors and are automatically changed over to doubly-fed motors by a limit switch or equivalent means at a predetermined point in the accelerating process and are subsequently subject to manual acceleration as doubly-fed motors. We have found that, in a system of the character designated, under certain conditions, as, for example, with an abnormally light load, the motor may start as a doubly-fed motor, with disastrous sparking. Furthermore, under abnormally heavy load conditions, with the

system indicated, it may be desirable to carry the point of change-over to an extremely late stage in the accelerating process in order to obtain sparkless operation and, were this attempted with the system of said prior application, there are two sequences of switch operation possible and, furthermore, there is a tendency to run ahead of the master controller and to give a jerky and abrupt acceleration, with unsatisfactory results, because of passing from repulsion operation to an advanced stage in the doubly-fed operation.

By the present invention, we provide means whereby the change-over to doubly-fed operation may be greatly delayed under abnormal load conditions but whereby when said change-over is effected, transition will always be made to the initial doubly-fed connection and, thereafter, the normal doubly-fed acceleration will be effected with consequent lack of abrupt changes in speed. Other novel control features of our system will be hereinafter pointed out.

In the accompanying drawings, Figure 1 is a diagrammatic view of the main circuits of a system of control embodying our invention; Fig. 2 is a diagrammatic view of the auxiliary governing system for the various motor-controlling switches shown in Fig 1; Fig. 3 is a sequence chart of well-known form for indicating the sequence of operation of the various switches; Figs. 4 and 5 are diagrammatic views of certain pieces of control apparatus that are employed in connection with my invention; Figs. 6 to 9, inclusive, are simplified diagrams of various main-circuit connections that are utilized during the operation of the motors.

Referring to Fig. 1 of the drawing, the system here shown comprises a pair of suitable supply-circuit conductors respectively marked "Trolley" and "Ground"; a transformer T provided with a primary winding P and a secondary winding S; a pair of alternating-current motors of the commutator type respectively having armatures M1 and M2, main or exciting field windings F1 and F2 and auxiliary or commutating field windings AF1 and AF2; a second pair of similar motors that are adapted to be connected in parallel relation with the first-mentioned pair and respectively having

2
 armatures M3 and M4, exciting field windings F3 and F4 and commutating field windings AF3 and AF4, all of the motors being adapted for operation from the secondary winding S of the transformer; a plurality of reversing-switches RS1 and RS2, preferably of the familiar electrically-controlled drum type, for respectively simultaneously reversing the electrical relations of the several pairs of motors, a plurality of motor-controlling switches 1 to 8, inclusive, A1, A2, B1, B2, C1, C2, R1 and R2, a suitable switch LS for connecting the primary winding P of the transformer to the supply circuit, a plurality of limit switches L1 and L2 of the differential type, having their main or preponderating actuating coils respectively disposed in circuit with the commutating field windings of the several pairs of motors and having their opposing or subordinate windings connected in parallel relation to the operating coil of the switch 1; a plurality of resistors RC1 and RC2 that are employed for short-circuiting the pairs of series-connected armatures M1 and M2 and M3 and M4, respectively; and a plurality of accelerating resistors, RR1, RR2, AR1 and AR2.

Referring now to Fig. 2, the auxiliary governing system shown comprises, in addition to the actuating coils for the various motor-controlling switches and the electrical interlocks of a familiar character that are respectively associated with certain of the switches, as illustrated in Fig. 4, a master controller MC that is adapted to occupy a plurality of operative positions *a* to *g*, inclusive, a master reverser of a familiar type; a suitable source of energy, such as a battery, B, for supplying energy through the master reverser and master controller to the various actuating coils; the auxiliary contact members of the limit switches L1 and L2, and a plurality of train-line conductors TL respectively corresponding to the several positions of the master controller, in accordance with customary practice.

In addition to the electrical interlocks that are movable with respective motor-controlling switches, a plurality of similar interlocks or contact members CO—10 to CO—16, inclusive, are disposed upon a change-over or cut-out drum CO for the motors, as diagrammatically illustrated in Fig. 5. The drum is adapted to occupy a plurality of positions, as indicated by the respective legends that are employed in the figure.

Assuming that the switch LS is closed, that the change-over switch CO occupies its position marked "All-in"; that the master reverser occupies its forward position and that the master controller is actuated to its initial operative position *a*, the operation of the system may be set forth as follows: A

circuit is first established from one terminal of the battery B through conductors 20 and 21, control fingers 22 and 23—which are bridged by contact segment 24 of the master controller—conductor 25, control fingers 26 and 27—which are bridged by contact segment 28 of the master reverser—conductor 29, train-line conductor 30, conductor 31, contact segment 33 of the reversing switch RS, in its forward position, conductors 34 and 35, interlock CO—12—All-in, the actuating coils of the switches A1 and 7 and conductors 36 and 37 to the opposite terminal of the battery B. Another circuit is simultaneously established from conductor 30 through conductor 38, contact segment 39 of the main reversing switch RS, conductors 40 and 41, interlock CO—11—All-in and the actuating coils of the switches A2 and 8 to the negative conductor 36.

A further circuit is completed from contact segment 42 of the master controller through control finger 43, conductor 44, train-line conductor 45, conductor 46, interlock 2-out, conductor 47 and 48, and the actuating coil of the switch 1 to conductor 36. Another circuit is established, at the same time, from contact finger 22', train-line conductor 30', conductor 46', interlocks 4-out and 3-out, conductor 47' and the parallel-connected actuating coils of the switches C1 and C2 to conductor 36.

The motors are thus started into operation as repulsion motors, the resistors RC1 and RC2 being connected across the pairs of armatures M1 and M2, and M3 and M4, respectively, and the parallel-connected pairs of motors are respectively connected in series-circuit relation, with the accelerating resistors RR1 and RR2 across a suitable portion of the secondary winding S of the transformer T, as indicated by the solid lines in Fig. 6.

Upon movement of the master controller MC to its second operative position *b*, a circuit is established from the contact segment 24 through control finger 49, conductor 50, train-line conductor 51, conductors 52 and 53 and the parallel-connected actuating coils of the switches R1 and R2 to the negative conductor 36.

The resistors RR1 and RR2 are thus short-circuited to effect a predetermined degree of acceleration of the motors, as indicated by the dotted lines in Fig. 6.

The transition of the pairs of motors to the doubly-fed connection may then be effected automatically in the following manner: A circuit is established from conductor 52, interlock R1—in and R2—in, as soon as the corresponding switches have closed, conductors 54, interlock 5—out, conductors 55 and 56, interlock CO—14—All-in, auxiliary contact members 57 of the limit switch L2, provided the motor current has

decreased to a predetermined value to allow the limit switch to occupy its lower position, and conductor 58 to a junction-point 59, whence one circuit is completed through 5 conductor 60, interlock 61—B1—out, conductor 62, interlock CO—10—All-in and the actuating coil of the switch B1 to the negative conductor 36, and a second circuit is completed from the junction-point 59 10 through conductor 63, interlock 64—B2—out, conductor 65, interlock CO—11—All-in, and the actuating coil of the switch B2 to conductor 36. As soon as the switches B1 and B2 are closed, holding circuits therefor 15 are formed, comprising conductors 62, interlock 61—B1—in and conductors 66 and 55 for the switch B1, and comprising conductor 65, interlock 64—B2—in, and conductors 67, 68 and 56 for the switch B2. 20 As soon as the switches B1 and B2 have closed, a circuit is established from conductor 68 through conductors 69 and 70, interlocks B1—in and B2—in, conductor 71, interlock 4—out and the actuating coil of the switch 25 3 to the negative conductor 36. The armature short-circuiting switches C1 and C2 are then opened by reason of the exclusion from their control circuit of the interlock 3—out. 30 Attention is directed to the fact that the preponderating actuating coils of the limit switches L1 and L2 are respectively connected in circuit with the commutating field windings of the respective pairs of motors, 35 whereby the transition of the motors to the doubly-fed connection, as just described, is effected when the current in the commutating field windings reaches the proper value to permit of good commutation during 40 the transition, which will ordinarily occur when the motors have attained what may be termed their synchronous speed. It should also be noted that, when the change-over switch CO occupies its "All-in" position, 45 the auxiliary contact members of the limit switch L1 are short-circuited by the interlock CO—14—All-in, whereby the transition to the doubly-fed connection is effected irrespective of the limit switch L1 and dependent solely upon the position of the limit switch L2. Inasmuch as the auxiliary contact members of the limit switches are connected in series-circuit relation, it will be appreciated that, unless the short-circuiting connection referred to was made, considerable time might be lost before the two limit switches would remain down simultaneously for a sufficient period of time to enable the switches B1 and B2 to close. The interlock CO—14—All-in, thus prevents such loss of time because of fluttering operation of the limit switches and tends to effect more stable and reliable operation of the system during the transition.

The doubly-fed connections of the respec-

tive pairs of motors are thus completed substantially as soon as the limit switch L2 drops to its lower position. The main circuit connections at this time are illustrated in Fig. 7.

Upon closure of the switch 3, a circuit is established from conductor 54, through conductor 72, and interlock 3—in to train-line conductor 74 which is connected to circuits in other vehicles of a multiple-unit train (not shown) to effect the closure of the switches that correspond to the switch 3 of this system substantially simultaneously with the closure thereof, thereby effecting the transition of the motors in the other vehicles to the doubly-fed connection at substantially the same time as the change is effected in the system illustrated. It is believed that this operation will be sufficiently familiar to those skilled in the art to obviate the necessity of any further illustration or description.

It will be noted that the master controller MC has remained in its position *b* during the transition of the motors to the doubly-fed connection, whereby the transition is effected automatically under the best commutating conditions, such automatic operation being preferable, as will be understood. However, if, for any reason, it is desired to otherwise energize the train-line conductor 74 to effect the transition of the motors in other vehicles, such operation may be effected by actuating the controller MC to its position *c*, whereupon the contact segment 24 engages control finger 75, and circuit is completed through conductor 76 to the train-line conductor 74. Thus, in the preferred operation, the transition of motors on other vehicles to the doubly-fed connection is accomplished automatically, and such transition corresponds to the inactive subsequent position *c* of the master controller, although the controller, at the time, occupies its preceding position *b*.

If, however, limit switch L2 does not fall as the master controller is moved forward, nothing occurs when contact is made with the finger 75 on the acceleration position *c*. Movement of the controller to the position *d*, however, energizes the train-line conductor 79 through the contact finger 78, and current flows via the conductor 80, interlock 3—in, conductor 81 and interlock 2—out and closes the switch 2, raising the motor voltage and holding the switch 2 in a closed position by a locking circuit from the conductor 69 through the interlock 2—in. The switch 1 thereupon opens by the exclusion from its operating circuit of the interlock 2—out.

Movement of the controller to the position *e* closes a circuit through train-line 85, conductor 86, interlock 1—out, and the actuating coil 5 to the main 36, closing the 130

switch 5 and imposing maximum voltage upon the motor while still maintaining the repulsion connection thereof.

In the circuit of the aforementioned application, the movement of the master controller to the position *f*, would energize the train-line conductor 89, and close the switch 4, thus passing from a high-voltage repulsion connection to an intermediate middle-tap connection, with a resultant abrupt change in speed and severe sparking. By the present system, this action is prevented by causing the actuating coil of the switch 4 to be energized through an interlock 5—in located on the drawing in proximity to the limit switch L1 and also through the contacts of the limit switch L2. By this means, if the master controller is moved too rapidly from the position *e* to the position *f*, nothing happens until the speed has sufficiently increased and the motor current sufficiently decreased to permit the limit switch L1 to fall. The first fall of said limit switch closes the switches B1 and B2 and, immediately thereafter, the switch 3, all as described in the companion application, and thus establishes the low-voltage, mid-tap connection. The closure of the switch 3 opens the switches C1 and C2 and thus re-moves the repulsion connection shown in Fig. 8. The switch 4 is not closed at this time, not only because the interlock 3—in is included in its circuit but also because it is interlocked at 61—in or 64—in. The next fall of the limit switch L1 energizes the actuating winding of the switch 4, closing the same and raising the mid-tap voltage, whereupon, movement of the master controller to the position *g* closes the switch 6 and permits full speed doubly-fed operation, as indicated in Fig. 9.

In the above-described semi-automatic acceleration, smoother operation is obtained by causing the limit setting for the differential limit switches L1 and L2 to be lower in the upper speeds than in the lower speeds and, for this purpose, the auxiliary or subordinate coils 92 and 93 thereof are connected in shunt to the actuating coil of the switch 1, as shown. When, therefore, the switch 1 is opened by the exclusion from the circuit thereof of the interlock 2—out upon the movement of the master controller to the position *d*, said subordinate or opposing limit switch operating coils are deenergized, producing the effect of a reduction in the limit setting.

It will be noted that by our system, with normal load, the change-over from repulsion to doubly-fed connection will occur at or about the third notch but, if the load is abnormally heavy, or if the master controller is moved ahead too rapidly, the repulsion connection may be maintained until the sixth or seventh notch. When, however,

the automatic change-over occurs, it takes place to the initial mid-tap connection and thereafter there is automatic mid-tap acceleration until the master controller is caught up with.

Assuming that, because of an accident or for any other reason, it is desired to cut the motors M1 and M2 out of operation, the change-over switch CO is moved to its second position marked "M1 and M2—out", whereby an interlock 11^a is substituted for the interlock 11 of the change-over switch, while the interlocks CO—10 and CO—12 are rendered inoperative by reason of the movement of the switch to its new position. Consequently, the switches A1, 7 and B1 cannot be closed, and only the circuits of the motors having the armatures M3 and M4 are operative.

Moreover, in the second position of the change-over switch CO, an interlock 13^a is substituted for the interlock 13, while the interlock CO—14 is excluded from circuit. At the same time, the interlock CO—16 engages control finger 97 and one of the control fingers that were bridged by the interlock CO—14, whereby the interlock CO—16 is substituted for the interlock B1—in and the switch 3 may thus be closed upon the closure of the switch B2, irrespective of the inoperativeness of the switch B1. Although the auxiliary contact members of the limit switch L1 are no longer short-circuited by the interlock CO—14, there will be no fluttering action of the limit switches, inasmuch as, since the circuit of the motors having the armatures M1 and M2 is dead, the switch L1 will remain in its lower position throughout the operation of the system.

If it is desired to exclude the other pair of motors from the circuit, the change-over switch CO is operated to its third position marked "M3 and M4—out" whereby interlocks 10^a and 12^a are substituted for interlocks 10 and 12, while the interlocks 11^a and 13^a are excluded from circuit. The switches A2, 8 and B2 are thus rendered inoperative, and only the circuit of the motors having the armatures M1 and M2 may be employed. At the same time, an interlock CO—15 bridges control fingers 96 and 97 of the change-over switch, whereby the interlock CO—15 is substituted for the interlock B2—in to permit operation of the switch 3, irrespective of the inoperativeness of the switch B2. Since the interlock CO—14 is excluded from circuit and the limit switch L2 will remain down, the transition of the motors having the armatures M1 and M2 to the doubly-fed connection will depend upon the position of the limit switch L1, which, in the other positions of the change-over switch, is inoperative.

While we have shown our invention in its simplest and preferred form, it is not so

limited but is susceptible of various minor changes and modifications without departing from the spirit thereof, and we desire, therefore, that only such limitations shall be placed thereupon as are imposed by the prior art or indicated in the appended claims.

We claim as our invention:

1. The combination with a source of alternating currents, of an alternating-current motor of the compensated, commutator type, means for producing connections therebetween, said means embodying control apparatus whereby said motor may be manually started and accelerated as a repulsion motor until the load current has fallen to a predetermined value, when transition to a doubly-fed connection is automatically effected and acceleration is thereafter effected as a doubly-fed motor, and means whereby the initial speed with doubly-fed operation at all times slightly exceeds the last speed with repulsion operation.
2. The combination with a source of alternating currents, of an alternating-current motor of the compensated, commutator type, means for forming connections therebetween, said means embodying a current-limit switch and attendant control apparatus whereby said motor may be manually started and accelerated as a repulsion motor until the load current has fallen to the setting of said limit switch, when transition to doubly-fed operation is effected, and means whereby, if said transition is unduly delayed, the setting of said limit switch is automatically reduced.
3. The combination with an alternating-current motor, of a controller for establishing certain accelerating connections for said motor, a relay responsive to predetermined motor-current conditions for automatically effecting a transition in said motor connections, and means for automatically changing the setting of said relay if said transition is not effected before a certain accelerating step is reached.
4. The combination with an alternating-current motor, of a controller for establishing certain accelerating connections for said motor, means including a relay responsive to predetermined running conditions of the motor for effecting a transition in said motor connections, and means for automatically changing the conditions of operation of said relay if said transition of motor connections is delayed beyond a predetermined step in said accelerating connections.

5. The combination with a source of energy and an electric motor, of means for producing two different types of connections therebetween, said means also embodying control apparatus whereby said motor may be manually started and accelerated with one type of connections until the operating conditions have reached a predetermined stage, when transition to the other type of connections is automatically effected, and means whereby the initial speed with the second type of connections at all times slightly exceeds the last speed with the first type of connections.

6. The combination with a source of energy and an electric motor, of means for forming two different types of connections therebetween, said means also embodying a current-limit switch and attendant control apparatus whereby said motor may be manually started and accelerated with one type of connections until the load current has fallen to the setting of said limit switch, when transition to the other type of connections is automatically effected, and means whereby, if said transition is unduly delayed, the setting of said limit switch is automatically reduced.

7. The combination with a source of energy and an electric motor, of means for producing connections therebetween corresponding to two different ranges of operation, means for normally effecting the transition from the one range to the other at a certain stage of the motor acceleration, and means responsive to relatively heavy-load conditions for delaying the identical transition till a later stage.

8. The combination with a source of alternating current, of an alternating-current motor of the commutator type, means for producing connections therebetween corresponding to repulsion and transformer-conduction operation, and a current-limit switch for normally effecting the transition from the one to the other set of connections at a certain stage of the motor acceleration, said switch being responsive to relatively heavy-load conditions for delaying the identical transition till a later stage and then effecting the progressive variation of transformer-conduction connections to a condition corresponding to said later stage.

In testimony whereof, we have hereunto subscribed our names this 29th day of Feb., 1916.

RUDOLF E. HELLMUND.
HURD T. MORRIS.
